UNITED STATES PATENT OFFICE

169,940

COMBINATION DRAFTING TABLE, DESK, AND BOOKRACK

Joel M. Jacobson, Irwin R. Barr, and Eugene J.
Tousignant, Baltimore, Md.

Application December 12, 1951, Serial No. 17,706

Term of patent 14 years

(Cl. D33—7)

To all whom it may concern:

Be it known that we, Joel M. Jacobson, Irwin R. Barr, and Eugene J. Tousignant, all citizens of the United States, all residing in the city of Baltimore, State of Maryland, have invented a new, original, and ornamental Design for a Combination Drafting Table, Desk, and Bookrack, of which the following is a specification, reference being had to the accompanying drawing, forming a part of the instant application, in which

Fig. 1 is a perspective view of a combination drafting table, desk, and bookrack, showing our new design; and

Fig. 2 is a view in perspective showing the opposite side of the combination drafting table, desk, and bookrack.

We claim:

The ornamental design for a combination drafting table, desk, and bookrack, as shown.

JOEL M. JACOBSON.

IRWIN R. BARR.

EUGENE J. TOUSIGNAN.
